Mr. Austine Smead, of Louisville, Kentucky
Letters Patent No 1762 dated May 26, 1863,

The schedule referred to in these Letters Patent and making part of the same.

To all whom it may concern:

Dec. 1762

Be it known that I, M. Austin Smead of the City of Louisville, in the County of Jefferson and State of Kentucky, have invented a new and original design for a Lady's or Gentleman's brooch and I do hereby declare that the following is a full and exact description of the same:

Fig No. 1 of the annexed drawings, shows the design of the "grand army brooch," the design of which is the same as that of an officer's regulation shoulder strap. It is to be made of metal enameled in different colors, according to the corps it has to represent, and I propose to introduce, on some of them, the different ornaments showing the respective ranks of the army from a Major Generalship to a Second Lieutenancy (see figs. 2, 3, 4, 5, 6, 7, 8.)

What I claim as my invention, is the design represented in the annexed drawings as Fig No 1 for Ladies or Gentleman's brooches or pins.
